FOUR DOOR CHEST

Joseph E. Adkinson, 3807 Leland St.,
Chevy Chase, Md. 20015

Filed Feb. 4, 1972, Ser. No. 223,826

Term of patent 14 years

Int. Cl. D6—04

U.S. Cl. D6—154

The single figure is a view in perspective of the four door chest showing my design.

The side not visible is identical to the side visible, and the top and bottom of the four door chest are plain.

I claim:

The ornamental design for a four door chest, or the like substantially as shown and described.
